UNITED STATES PATENT OFFICE

ALLEN E. BRICKMAN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TAKE-UP MECHANISM FOR LOOMS

Application filed October 11, 1929. Serial No. 399,056.

This invention relates to looms and particularly to take-up mechanism therefor. In such looms, it is desired to disable the take-up mechanism when the loom is stopped, so that the lay may be moved backward or forward without causing a taking up of the cloth.

It is preferred in some mills that the take-up be disabled by lifting the feed pawl out of contact with the ratchet, so that no further movement of the ratchet can take place so long as the shipper handle is in stopping position.

In other mills, it is desired that the take-up be disabled by lifting the holding pawl out of contact with the ratchet. In this latter case, the feed pawl can rock the ratchet as usual, but the advance position of the ratchet wheel is not retained by the holding pawl, so that the ratchet merely rocks back and forth over a slight arc in unison with the movement of the feed pawl, but no progressive advance movement of the ratchet occurs.

It is the object of my invention to provide a take-up mechanism so designed that it may be easily adapted to release either the take-up or the holding pawl, as may be desired under selected operating conditions.

My invention further relates to arrangements and combinations of parts which will be hereinafter described and more particularly pointed out in the appended claims.

A preferred form of the invention is shown in the drawings in which

Fig. 1 is a side elevation of parts of a loom embodying my improved take-up mechanism;

Fig. 2 is a front elevation thereof;

Fig. 3 is an enlarged plan view of certain parts;

Fig. 4 is an enlarged sectional side elevation, taken along the line 4-4 in Fig. 3;

Figs. 5 and 6 are views similar to Fig. 4, but showing the mechanism set to disable the feed pawl; and

Figs. 7 and 8 are views similar to Figs. 5 and 6, but showing the mechanism set to disable the holding pawl.

Referring to the drawings, I have shown

certain parts of a loom including the loom frame 10 and the lay 11 mounted on swords 12 and swinging about the axis of a rock shaft 13. The fabric F passes over a breast beam 14 to a take-up roll 15 by which the cloth is drawn forward in the usual manner. The roll 15 is provided with a ratchet wheel 16 fixed to the shaft or gudgeon 18 thereof and determining its advance movement.

A feed lever 20 is mounted on the shaft or gudgeon 18 of the take-up roll 15 and is rocked thereon by a link 22, by which the lever 20 is connected to an arm 23 on the rock shaft 13. A feed pawl 24 is pivoted at 25 to the feed lever 20 and is held in contact with the ratchet 16 by a spring 26.

A holding pawl 30 (Fig. 4) is pivoted at 32 in a segmental slot 33 formed in the end of an arm 34 which is maintained in fixed position on the loom frame. The holding pawl 30 is yieldingly forced against the ratchet 16 by a tension spring 35. The studs 25 and 32 are placed as near as practical to the ratchet 16, so that the engaging end of either one of the pawls may leave the ratchet teeth by a substantially radial movement and will consequently re-enter the same tooth space when returned to operative position.

As the lay 11 swings back and forth, the rock arm 23 swings the feed lever upward and downward, causing the feed pawl 24 to intermittently advance the ratchet 16, while at the same time any rearward movement of the ratchet is prevented by the holding pawl 30.

A shipper or knock-off lever 40 is keyed to a stud 42, pivotally mounted adjacent the ratchet 16, and is provided with a pair of openings 43 and 44 each adapted to receive an engaging stud. A release lever 50 is also pivoted on the stud 42 and is similarly provided with a pair of openings 53 and 54, also adapted to receive an engaging stud.

A pair of studs 55 and 56 are provided, the stud 55 fitting either one of the openings 43 or 53 and the stud 56 fitting either one of the openings 44 or 54. When one of the studs is placed in an opening of the lever 40, the other stud is placed in the

oppositely positioned opening of the lever 50.

When the stud 55 is in the opening 43 of the lever 40 and the stud 56 is in the opening 54 of the lever 50, as shown in Figs. 3 to 6, the operation of the device is as follows:—

The normal running position is as indicated in Fig. 4, with the stud 55 in position to engage the tail 24^a of the feed pawl 24. When the shipper lever 40 is swung to the stopping position indicated in Fig. 5, the stud 55 engages the tail 24^a and raises the feed pawl 24 from the ratchet 16, thus disabling the feed. If the weaver thereafter desires to entirely release the ratchet wheel so that the tension on the cloth may be relieved, he swings the release lever 50 from the position shown in Fig. 5 to the position shown in Fig. 6. By such movement, the stud 56 in the lever 50 engages a lug or projection 30^a of the holding pawl 30, raising the same to the inoperative position shown in Fig. 6.

A cross pin 60 (Fig. 6) is inserted in recesses 61 in the end of the lever 50 and prevents displacement of the lever 50. A shoulder 63 is formed on the lever 50 and engages a fixed stud 64, thus limiting swinging movement of the lever 50 under the influence of the spring 35.

If it is desired to release the holding pawl when the shipper handle is thrown off, the studs 55 and 56 are shifted to the openings 53 and 44 respectively, as indicated in Figs. 7 and 8, and the shipper or knock-off lever 40 then acts through the stud 56 to engage the lug 30^a and raise the holding pawl, as indicated in Fig. 7.

The release lever 50 can thereafter be swung to the position shown in Fig. 8 to engage the tail 24^a and render the take-up pawl 24 inoperative when it is desired to release all tension on the cloth.

I have thus provided a very convenient mechanism by which the take-up and holding pawls may be released in either of two desired orders. Either the take-up pawl may be released with the shipper lever and the holding pawl with the release lever, or the holding pawl may be released with the shipper lever and the feed pawl with the release lever.

I am thus able to provide a single set of parts by which the take-up mechanism may be adapted to operate under the requirements of mills which desire either the one or the other sequence of operations as above defined.

Having thus described my invention and the advantages thereof, I do not wish to be limited to the details herein disclosed, otherwise than as set forth in the claims, but what I claim is:—

1. A loom take-up mechanism comprising a ratchet, a feed pawl, a holding pawl, a

shipper lever, a release lever, and means by which either lever may be rendered effective to disable either pawl.

2. A loom take-up mechanism comprising a ratchet, a feed pawl, a holding pawl, a shipper lever, a release lever, each of said levers having an opening at each side of the pivot thereof, and a pair of studs each insertable in an opening in either lever, said studs being effective to engage and disable said pawls in a selected sequence. 70

3. A loom take-up mechanism comprising a ratchet, a feed pawl, a holding pawl, and means to stop the loom and to substantially simultaneously disable one of said pawls, 80 said disabling means including a device having two different settings, said device in one setting rendering said means effective to disable one pawl and in the other setting rendering said means effective to disable the 85 other pawl.

4. A loom take-up mechanism comprising a ratchet, a feed pawl, a holding pawl, means to stop the loom and to substantially simultaneously disable one of said pawls, and 90 means to thereafter disable the other pawl, said first and second disabling means including separate devices associated with said first and second means and each having two settings, each device in one setting rendering its associated means effective to disable one pawl and in the other setting rendering said means effective to disable the other pawl. 95

In testimony whereof I have hereunto 100 affixed my signature.

ALLEN E. BRICKMAN.
